COMBINED STEREO SPEAKER UNIT AND HIGH FIDELITY CABINET SUPPORT

Alfred William Faux, Toronto, Ontario, Canada, assignor to Clairtone Sound Corporation Limited, Rexdale, Ontario, Canada

Filed Sept. 16, 1965, Ser. No. 87,021

Term of patent 14 years

(Cl. D26—14)

FIG. 1

FIG. 2

FIG. 3

FIG. 4.

FIG. 1 is a front elevational view of a combined stereo speaker unit and high fidelity cabinet support embodying my new design;

FIG. 2 is a top plan view;

FIG. 3 is a side elevational view; and

FIG. 4 is an enlarged fragmentary sectional view taken through line 4-4 of FIG. 1.

I claim:

The ornamental design for a combined stereo speaker unit and high fidelity cabinet support, as shown.
